UNITED STATES PATENT OFFICE.

JAMES E. BELL, OF WASHINGTON, DISTRICT OF COLUMBIA.

RIFLE-BULLET.

No. 807,012.

Specification of Letters Patent.

Patented Dec. 12, 1905.

Application filed June 26, 1905. Serial No. 266,980.

To all whom it may concern:

Be it known that I, JAMES E. BELL, a citizen of the United States, residing at Washington, in the District of Columbia, have invented certain new and useful Improvements 5 in Rifle-Bullets, of which the following is a specification.

The service-bullets employed in the United States and other military rifles having a caliper of about thirty-hundredths of an inch have a length which is several times their diameter. To maintain the axes of these long bullets in the line of flight, it is necessary to give them a rapid axial rotation. To effect 15 this rotation, the bore of the United States rifle has four helical grooves with a pitch of ten inches, the width of each groove being 0.1767 inch and its depth 0.004 inch, the width of the intermediate lands being 0.0589 20 inch. On account of this rapid twist a soft-lead bullet cannot be used in military rifles, as when driven through the barrel with high velocity by a charge of smokeless powder the bullet will not follow the grooves, and the 25 lands will shear off the portions of the lead lying in the grooves. It is therefore usual to employ a composite bullet having a soft core of lead and a thin jacket of harder metal, such as a nickel-copper alloy, the core giving the 30 necessary weight, while the jacket holds the indentations produced by the lands. The jacketed bullets give satisfactory results so far as accuracy is concerned, but have serious defects. A considerable portion of the 35 energy of the powder charge—said to be forty per cent—is required to drive the bullet through the barrel. This consumption of energy is largely due to the fact that the bullet when expelled from the cartridge must 40 constantly conform itself to the shape of the rifled bore, the lands pressing spiral recesses into the cylindrical portion of the bullet, which is usually about five-eighths its total length. Time is required to effect this 45 change in the shape of the bullet, and its movement through the barrel is thereby retarded. The friction between the barrel and the long cylindrical body of the bullet also retards the bullet, so that the pressure of the 50 powder-gases rises to a high figure, while the metal of the barrel is worn away by the hard-metal jacket to such an extent that it soon gives inaccurate results.

The present bullet also consists of a soft- 55 metal core and a jacket of harder metal; but

the body of the bullet is not of uniform diameter. The bullet comprises a point of the usual form, a relatively long cylindrical body having a diameter substantially equal to the bore of the rifle in which it is to be used, and 60 a relatively short cylindrical base portion having a diameter substantially equal to that of a circle coincident with the base of the grooves of the rifle.

Referring to the accompanying drawings, 65 Figure 1 is a side elevation of the improved bullet. Fig. 2 is a side elevation of the bullet-core, showing the jacket in vertical section. Fig. 3 is a side elevation of a rifle-barrel, showing the bullet in elevation therein. 70 Fig. 4 is a transverse section on the line 4-4 of Fig. 3, and Fig. 5 is a transverse section on the line 5-5 of Fig. 3.

The bullet chosen for illustration is designed 75 for the United States Army rifle, and consists of the core 1 and the jacket 2. The bullet comprises a point 3, a long body portion 4, and a base portion 5, there being a tapering shoulder 6 between the portions 4 5. The diameter of the body portion 4 is substantially 80 equal to the bore of the United States rifle—that is, 0.300 inch. It is therefore adapted to bear smoothly and with little friction upon the lands 9 of the rifle 7, as shown in Figs. 3 and 5. The base portion 5 is intended 85 to take the rifling and rotate the bullet and to serve as a gas-check. Its diameter is substantially equal to that of the circle coincident with the base of the grooves of the rifle—that is, about 0.308 inch. It has been found 90 by experiment that the length of the base portion need not exceed one-half the diameter of the bullet—that is, 0.15 inch. This length is sufficient to rotate the bullet without stripping and to prevent the escape of the powder- 95 gases. The rifle-lands 9 press short helical indentations 10 into the base portion, while the base fills the grooves, as shown in Figs. 3 and 4.

Careful tests of the improved bullet in the 100 United States Krag-Jorgensen rifle have shown that under otherwise identical conditions with a charge of 33.4 grains of Laflin and Rand W. A. smokeless powder this bullet reduces the average pressure of the powder- 105 gases in the barrel from thirty-two thousand four hundred and twenty pounds per square inch with the standard bullet to twenty-seven thousand nine hundred and sixty pounds without substantially affecting the 110

velocity or accuracy. Similar tests in the United States Springfield rifle, model of 1903, with a charge of forty-four grains of smokeless powder have shown an average reduction of 5 pressure from forty-two thousand eight hundred pounds per square inch to thirty-six thousand pounds without change in the velocity. The reduced pressures due to the use of the improved bullet enable the standard powder charge to be increased, thereby giving the bullet a velocity greater than that heretofore obtained. The accuracy of the bullet with such increased charges seems to be increased, so far as determined. The wear 15 of the rifle-barrel should apparently be decreased by the use of a bullet with the short bearing and decreased area of frictional contact.

It will be understood that the specific dimensions shown and described can be slightly modified without departing from the invention and that the proportions of bullets for rifles other than the United States one are dependent on their bore and the depth of their 25 grooves.

I claim—

1. A service-rifle bullet, consisting of a soft core and a thin jacket, said bullet comprising a relatively long cylindrical body portion having a diameter substantially equal to the bore of the rifle and a relatively short cylindrical base portion having a diameter substantially equal to that of a circle coincident with the base of the grooves of the rifle, as set forth. 30

2. A bullet for the United States service-rifle, consisting of a soft core and a thin jacket said bullet comprising a relatively long cylindrical body portion having a diameter of about three hundred thousandths of an inch 40 and a relatively short cylindrical base portion having a diameter of about three hundred and eight thousandths of an inch, as set forth.

In testimony whereof I affix my signature 45 in presence of two witnesses.

JAMES E. BELL.
